United States Patent

Des. 238,475
Patented Jan. 20, 1976

238,475

TRAY

Leland H. Logue, 150 S. Marion Parkway,
Denver, Colo. 80209

Filed Apr. 19, 1974, Ser. No. 462,238

Term of patent 14 years

Int. Cl. D7—99

U.S. Cl. D7—20

FIG. 1 is a perspective view of a tray showing my new design;

FIG. 2 is a bottom view thereof;

FIG. 3 is a top view thereof;

FIG. 4 is a side elevational view thereof; and

FIG. 5 is another side elevational view thereof.

I claim:

The ornamental design for a tray, as shown.
